(57) **CLAIM**

The ornamental design for a cross tube connector, as shown and described.

DESCRIPTION

FIG. 1 is a bottom, perspective view of a cross tube connector;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The subject matter shown in dashed lines, and any surfaces of the design not shown, form no part of the claimed invention.
